CLAIM

The ornamental design for an operator cab for an
agricultural machine with mounting wings therefor, as
shown and described.

DESCRIPTION

FIG. 1 is a left front perspective view of the operator
cab for an agricultural machine with mounting wings
therefor, showing our new design;

FIG. 2 is a front elevational view thereof, the broken
lines showing rear view mirrors and lights are for illus-
trative purposes only and form no part of the claimed
design;

FIG. 3 is a front right perspective thereof; and

FIG. 4 is a right rear perspective view thereof.
